AIR CONTROL SYSTEM
 George V. Bardet, Berkeley, Calif., assignor to
 M.J.B. Co., a corporation of Delaware
 Filed Jan. 4, 1960, Ser. No. 268
 2 Claims. (Cl. 34—87)

This invention relates to a method of sealing air ducts to a series of trays as the trays are intermittently passed through a machine. More specifically, the invention has its primary application to a rice processing machine such as is described in application Serial No. 786,141, filed January 12, 1959, now Patent No. 3,006,269. In said patent application a machine is described wherein a series of trays are carried on endless chains past a series of stations. Mechanism is provided whereby the chains move intermittently so that the trays are alternately stopped under a filling station, a heating station, two separate cooling stations and then discharged into a bin. In the heating station, hot air is blown from a duct through the material on the trays and at the two cooling stations cold air is blown through the material. It is obvious that in any such system it is important that a good seal be effected between the tray and the ducts. The present invention is directed towards a structure and mechanism whereby a substantially airtight seal is made with the duct work, both above and below the tray, as each tray is stopped at the successive stations.

In the drawings forming part of this application:

FIGURE 1 is a side elevation, partially diagrammatic, showing the overall structure of a rice treating machine embodying the present invention.

FIGURE 2 is a section on the line 2—2 of FIGURE 1 showing the sealing mechanism in detail.

FIGURE 3 is a section on the line 3—3 of FIGURE 1 showing the upper bellows structure.

FIGURE 4 is a plan view of a sealing frame.

FIGURE 5 is a diagrammatic side elevation showing the relationship between the sealing frames and the path of travel of the trays.

FIGURE 6 is an enlarged section on the line 6—6 of FIGURE 4.

FIGURE 7 is an enlarged side elevation of a portion of FIGURE 1.

Turning now to a description of the invention by reference characters, there is shown a machine having a main framework generally designated 4 and having attached thereto a subframe 5. Mounted within the framework are a series of sprockets 6 around which is trained a pair of endless chains 8. Only one pair of chains is shown in the side elevation but a second identical set is located on the opposite side of the treating chamber as is more fully brought out in the above identified pending application. The chains 8 carry a series of trays 10 suspended between them. At the heating station a duct 12 is provided leading to an air heater, not illustrated. Directly above this duct 12 is a second duct 14, which may lead to the atmosphere or which may return all or a portion of the air to the air heated for reheating and recycling. At the cooling stations a duct 16 leads from a fan or blower to the two ducts 18 and 20 while directly over these ducts are provided the exhaust ducts 22 and 24 which lead to the common duct 26 which goes to the atmosphere. It will be understood that the ducts 12 and 14 together with the associated mechanical equipment constitute a heating station while the ducts 18 and 22 as well as 20 and 24 constitute two cooling stations. As is set forth in the aforesaid patent application, the chains 8 are given a start-stop motion so that the trays 10 are successively filled, brought to the heating station, stopped while the heating operation takes place, moved to the first cooling station and so on.

2

In FIGURES 2 and 7 there is shown in detail the exact relationship between the ducts and the tray. The endless chains 8 ride on the rail 28 and pairs of adjacent links of the chain carry the members 30. The members 30 in turn ride on the guide rails 32. The main rails 28 extend beyond the heating chamber as is shown at 28A and 28B, respectively, in FIGURE 7. The trays themselves are of generally circular configuration and have a side wall 34 and a screen bottom 36. The members 30 are welded to the trays, as is shown in FIGURE 2, and serve to support the trays. The trays also have a top sealing flange 38 and a bottom sealing flange 40.

Mounted above the end of duct 12, and spaced therefrom, is the bottom tray sealing ring 42. The ring 42 is connected to the duct 12 by a flexible member 44, suitably asbestos fabric. Mounted below the duct 14 is the upper tray sealing ring 46. The upper sealing ring 46 is connected by the flexible member 48 to the duct 14 which may be of the same material as the member 44. It is thus apparent that the lower sealing ring 42 and the upper sealing ring 46 can each be displaced a substantial distance vertically, yet still retain an airtight relationship with the ducts 12 and 14 respectively. In addition, the lower sealing ring 42 is provided with a gasket 50 while the upper sealing ring is provided with a gasket 52. The gaskets 50 and 52 are of a relatively soft, heat resistant, resilient material. Silicone rubber is well suited for this purpose. It will be apparent from FIGURES 2 and 7 that if the upper sealing ring 46 is lowered and the lower sealing ring 42 is raised, a substantially airtight seal will be provided with the flanges 38 and 40 and the tray 10.

Although only one lower sealing ring and upper sealing ring and associated equipment have been described, in actuality three identical sets of upper and lower rings are provided for the heating station and the two cooling stations, all as is shown in the drawings.

In order to actuate the several sealing rings in unison, two movable sealing frame 54 and 68 are provided. The sealing frames are identical and are shown in plan view in FIGURE 4 and a section of the frame is shown in FIGURE 6. The frames consist of side rails 55 and 57 and cross rails 59, forming a series of square compartments. The rails are all of the box-like construction shown in FIGURE 6. Oblong holes 61 are provided for attachment of the brackets which hold the sealing rings. The top sealing frame 54 is fastened to the top sealing ring 46 by means of the L-shaped bracket 62 and the bolt 64. By the use of the double nuts 56 and 56A, as well as the oblong holes 61, precise positioning is possible. To facilitate the fastening, an alloy ring 66 is provided on the upper sealing ring 46. A bolt 65 holds the ring 66 to the bracket 62. To provide a similar action for the bottom sealing ring the bottom sealing ring the bottom sealing frame 68 is provided. The bottom sealing frame 68 is fastened to the bottom sealing ring 42 by means of the L-shaped bracket 70 and the bolt 71. A bolt 72 passes into the ring 74 which is attached to the sealing ring 42. Precise positioning is provided as described above. Here again it will be understood that the top sealing frame is fastened to all of the top sealing rings while the bottom sealing frame is attached to all of the bottom sealing rings, so that as each frame moves, all of the corresponding sealing rings move in unison.

To provide a means of actuating the top and bottom sealing frames, and thus the sealing rings, in unison a first bell crank 76 is provided which is attached to the shaft 78 which is mounted for rotation on the subframe 5. A bell crank 80 of similar structure is attached to shaft 82 and the arms are connected together a short distance from their fulcrums by the rod 84 so that the cranks operate in unison. Corresponding arms of each of the bell

cranks are linked through the rods 86 to the top sealing frame 54. The opposite arms of each of the bell cranks are linked by means of the rods 88 to the lower sealing frame 68. The shafts 78 and 82 extend to the opposite side of the machine where the bell cranks and rods are duplicated, so that both sides of both sealing frames are actuated together. The connecting rod 89 of pneumatic cylinder 90 is linked to the bell crank 76 as illustrated. Thus, as the piston of the cylinder 90 is actuated to the right the bell cranks 76 and 80 are rotated in a clockwise direction on their shafts, lowering the upper sealing frame 54 and raising the lower sealing frame 68 so that the parts are brought in sealing relationship as is illustrated in FIGURE 2. A movement to the left reverses the process and frees the trays so that they can be moved.

The lines 91 and 93 of cylinder 90 are connected to the corresponding lines of controller 92 which is also connected to the drive motor assembly 94 so that the trays and sealing mechanism are actuated in synchronism. In other words, pressure is first applied through line 93 which releases the upper and lower sealing rings, freeing the series of trays, and the controller causes the motor 94 to advance the trays one position and stop. Pressure is then applied to line 91, bringing the parts into sealing relationship, whereupon air can be blown through the trays. At the end of the blowing cycle, the series of steps is repeated, as described.

I claim:

5. In a machine for treating a particulate solid wherein the solid is placed on a tray, passed between upper and lower air ducts wherein air is blown through the tray, and the trays then removed from the ducts, the improvement comprising an upper sealing ring on the upper duct and a lower sealing ring on the lower duct, a plurality of substantially airtight flexible members, one of said members connecting each of said sealing rings to its respective duct and means whereby said upper sealing ring and said lower sealing ring may be moved towards each other to grasp a tray therebetween and establish substantially airtight communication with said tray, and means whereby said upper sealing ring and said lower sealing ring can be moved in opposite directions to release said tray.

10. The machine of claim 1 wherein a series of trays and an endless belt are employed said belts carrying said trays and wherein a controller brings each tray successively in juxtaposition with said ducts, said controller causing said sealing rings to be actuated into sealing relationship and subsequently causing said rings to be actuated in opposite directions and said controlling means causing a repetition of the cycle.
